CRIMPING TOOL

Marion B. Holmes, Drayton Plains, Mich., assignor to General Dynamics Corporation, San Diego, Calif., a corporation of Delaware

Filed Aug. 14, 1963, Ser. No. 302,170
7 Claims. (Cl. 72—402)

The present invention relates generally to crimping tools and more particularly to crimping tools that are selectively adjustable to positively effect a given indentation in crimping a connector conductor combination.

In using known crimping tools to crimp connectors on to conductors, it is often difficult to consistently effect standard indentations for different size connectors. This problem is compounded where the size of the connectors vary widely or where the connectors have wide ranges of wall thicknesses and tempers. However, it is obviously advantageous to have a crimping tool capable of positively crimping to a given standard all makes, sizes and tempers of connectors, without having to make extensive manual and physical adjustments to the tool.

Therefore, it is an object of this invention to provide an improved crimping tool that can be selectively adjusted to positively crimp various sizes of connectors to a desired indentation.

Other objects and many attended advantages of this invention will be readily apparent as the same becomes better understood by reference to the following description and with the accompanying drawings in which like reference numerals designate like parts throughout the figures thereof and wherein:

FIGURE 1 is a side elevational view of a crimping tool of this invention with part being broken away and in section and with the handle in the open position.

FIGURE 2 is a side elevational view of the crimping tool of this invention with part broken away and in section and with the handle being in the partially closed position.

FIGURE 3 is a side elevational view of the crimping tool of this invention with part being broken away and in section and with the handle being in the closed position.

FIGURE 4 is a side view of a part of the crimping tool illustrating the indentor gap control and the indicator panel.

FIGURE 5 is a cross-sectional view of FIGURE 4 taken along lines 5—5.

FIGURE 6 is a top view of the indentor gap control.

FIGURE 7 is a composite view of parts of the crimping tool broken out in an exploded view.

Referring now to the drawings, a crimping tool, generally indicated by the numeral 10, includes a pair of handle members 11 and 12, adapted for pivotal interconnection at one of their ends. Handle member 12 comprises a U-shaped body portion having a pair of joined side plates, see FIGURE 5, with aligned apertures 51 extending through the side plates for receiving the connector to be crimped. In FIGURE 7 only one side of the pair of side plates 12 is shown. Also extending through the side plates are a plurality of aligned slotted apertures 50 that lie in a circle concentric about the apertures 51. Handle 11 has an enlarged end portion 61 integrally connected with an elongated portion 62 and a reinforcing portion 63. An enlarged opening 39, see FIGURE 7, extends through the enlarged end portion 61 and is provided with a plurality of equally spaced cam surfaces 25, preferably four in number.

A cylindrical punch holder 24, having a central aperture 68 aligned with apertures 51 in the side plates of the handle 12, is disposed within the enlarged opening 39 in

2

the handle 11. A plurality of equally spaced, transverse grooves, 70 are formed in the punch holder. Radial passageways 71 connect the inner surfaces of the grooves 70 with the aperture 68. Within each of the grooves 70 is positioned a punch member 22 having an enlarged head portion 73 with an arcuate outer surface adapted for slidable engagement with the adjacent cam surface 25, and an integral cylindrical body portion 74 that extends into the passageway 71 and forms the punch that crimps the connector. The punch end of the body portions 74 are ground to a substantially pointed shape whereby the crimp indentations are more readily formable. Each of the body portions 22 are resiliently biased by a spring 25 that continuously urges the arcuate head 73 into contact with the corresponding cam surfaces 25. The punch holder 24 is connected to the side plates of the handle member 12 by means of bolts 23 that extend through slotted apertures 50 in the side plates and through the apertures 78 in the punch holder 24.

Also positioned between the side plates of the handle member 12 and the arm 11 and enclosing the punch holder 24 within the recess of the enlarged head portion 61 of the handle 11, is the gauging means 13. Bolts 23 pass through apertures 80 to fix the gauge member 13 in exact and positive relationship with the punch holder 24. However, it may be seen that both the punch holder 24 and the gauging member 13 may be rotatably moved relative to the side members of the handle member 12 through movement of bolt 23 within the slotted apertures 50.

Referring now to FIGURE 1, the handle members are shown joined, with the punch holder 24 and punches 22 inserted within the handle member 11 and in position for crimping. Positioned within the bottom of the U of the U-shaped portion of handle 12 is a member 19 having a longitudinal portion 68 and an end portion 69. Mounted on the upper surface of the longitudinal portion 68 is a track member 15 on which is positioned a slidable indentor gap control member 14. As may be seen the indentor gap control member 14 may be slidably moved longitudinally along the upper surface of the track member 15. Indentations 85 on the underneath surface of the indentor gap control member 14 coact with ball detent device 17 that is resiliently biased by spring 18. The ball resiliently holds member 14 in a given position from which it may be selectively moved by exerting sufficient pressure. Thus, member 14 may be selectively moved along the track to a position of its furthest movement toward the crimping end as is shown in FIGURE 1. Pin 31 secures the member 19 to the desired position within the U-shaped handle member 12.

Gauge member 13 is positioned in the manner wherein the undersurface of end 88 rests upon some portion of the indentor gap control member 14. Indentor gap control member 14 has a series of stair-stepped shoulders 89 on which the end 88 of the gauge member 13 may be selectively placed, depending upon the longitudinal positioning of the member 14 along track 15. Spring member 16 resiliently biases the end 88 of member 13 to a position wherein it is spaced above the highest point of the indentor gap control member 14 when the arms 11 and 12 are in the open position.

A pawl member 28 is toggled to one of two positions by spring 33 and has a serrated portion 38 that coacts with projection 35 on handle 11 for holding the handles 11 and 12 to a given position during the closing movement. A stop member 27 mounted on the upper surface of the end of the end portion 69 contacts the reinforcing portion 63 limiting further inward movement of handles 11 and 12 during closure to the full crimped position.

The indentor gap control member 14 has a pin 90 that projects from the side of the handle 12 through aperture

91. This pin coacts with a selector member 20. Mov-
able member 20 has an upper projection 26, which in con-
junction with a scale 21, indicates the desired wire size
for a given positioning of member 14 and the spacing of
the punches that will be ultimately obtained during crimp-
ing. Apertures 48 and 49 of the scale and selector mem-
bers align to receive a cotter pin type member for lock-
ing the indentor gap control member or spacer portion 14
in a given position. See FIGURES 4 and 6.

In operation, referring now to FIGURE 1, the handles 11 and 12 are in their fully opened position. Spring member 16 has resiliently biased the gauge member 13 to a position where lip portion 88 is out of contact with the indentor gap control mechanism 14. As may be surmised, if the handles were closed in the given position of indentor gap control mechanism 14, then the greatest degree of inward movement of the punches 22 would result. This corresponds on the selector wire scale 21 to the size wire on which a connector is to be crimped.

Referring now to FIGURE 2, the indentor gap control member 14 has been moved against the spring biased detent 17 along the track 15 by moving member 20. Thus, end 88 of the gauge member 13 is to contact the indentor gap control mechanism 14 on a shoulder displaced two positions downwardly from the position of largest radial inward movement of the punches 22. In closing the handle members 11 and 12, the enlarged end of the handle member 11 is rotated, thereby rotating the punch holder 24 and circumferentially rotating pins 23 in the longitudinal slots 50. When the end 88 of member 13 contacts the upper surface of the indentor gap control mechanism 14, then further movement of the gauge member 13 is stopped. Further movement of the handle 11 without corresponding movement of the punch holder 24 will cause bolts 23 to reach the other side of slots 50 and then the 30 cam portion of the punch members 22 will ride up on the cam surfaces 39 and be forced radially inwardly to crimp the contact 40. As shown in FIGURE 3, the complete closing of the handle member 40 has moved the punch members 22 into their furthest radially inward position 40 for the particular position of the indentor gap control member 14.

When the handles are in the open position, pawl 28 is rocked to a position wherein projection 35 does not contact the serrated portion 38. Closing movement of the handles will cause projection 35 to contact the serrations of serrated portion 38 and to coact therewith preventing any opening of the handle members. Thus, it may be seen that the handle members must move to the fully closed position as shown in FIGURE 3, whereupon projection 35 will push the bottom portion of the pawl member 28 to a point where the spring 33 will flip the pawl member 28 into a non-contacting position with projection 35. This releases the handles allowing them to be opened. Upon opening the handle members, projection 35 then 55 contacts the upper portion of the pawl member 28 pushing it to the position as shown in FIGURE 1.

When in the fully closed position, the reinforcing portion 63 of handle member 11 contacts stop members 27 preventing further closing of the handle members.

Although only the preferred embodiment of the invention has been shown and described herein, it is not to be construed that the invention is limited thereto, as numerous modifications will be apparent to those skilled in the art; and the invention is to be given its broadest interpretation within the terms of the following claims:

I claim:

1. A crimping tool for attaching a connector to the end of a conductor comprising in combination:

first and second handle members pivotally intercon-
nected at one of their ends and being capable of
movement between open and closed positions,
punches radially disposed at said interconnection of
said first and second handle members that rotate 75

circumferentially during movement of said handle members,
punch forcing means for forcing said punches radially inward in a direction toward intersection of said punches during portions of said circumferential movement of said punches,
said punch forcing means being selectively actuated by said pivotal movement of said handles to force said punches radially inward a distance proportional to the circumferential movement of said handles,
gauge means coacting with said pivotal movement of said handles for actuating said punch forming means upon a given pivotal movement of said handles,
and means for selectively varying the point in said circumferential movement of said handles at which said gauge means is actuated.

2. A crimping tool for attaching a connector to the end of a conductor comprising in combination:

first and second handle members pivotally intercon-
nected at one of their ends and being capable of
movement between open and closed positions,
stop means for preventing said movement of said handles beyond said closed position which closed position is at a single distance between said handles,
punches radially disposed at said interconnection of said first and second handle members that rotate circumferentially during movement of said handle members,

punch forcing means for forcing said punches radially inward in a direction toward intersection of said punches during portions of said circumferential movement of said punches,

said punch forcing means being selectively actuated by said pivotal movement of said handles to force said punches radially inward a distance proportional to the circumferential movement of said handles during the movement of said handles between actuation of said punch forcing means and said stop means,
gauge means coacting with said pivotal movement of said handles for actuating said punch forming means upon a given pivotal movement of said handles,
and means for selectively varying the point in said circumferential movement of said handles at which said gauge means is actuated.

3. A crimping tool for attaching a connector to the end of a conductor comprising in combination:

first and second handle members pivotally intercon-
nected at one of their ends and being capable of
movement between open and closed positions,
stop means for preventing said movement of said handles beyond said closed position which closed position is at a single distance between said handles,
punches radially disposed at said interconnection of said first and second handle members that rotate circumferentially during movement of said handle members,

punch forcing means for forcing said punches radially inward in a direction toward intersection of said punches during portions of said circumferential movement of said punches,

said punch forcing means being selectively actuated by said pivotal movement of said handles to force said punches radially inward a distance proportional to the circumferential movement of said handles during the movement of said handles between actuation of said punch forcing means and said stop means,
and gauge means coacting with said pivotal movement of said handles for actuating said punch forming means upon a given pivotal movement of said handles.

4. A crimping tool for attaching a connector to the end of a conductor comprising in combination:

first and second handle members pivotally intercon-
nected at one of their ends and being capable of
movement between open and closed position,

stop means for preventing said movement of said handles beyond said closed position which closed position is at a single distance between said handles, punches radially disposed at said interconnection of said first and second handle members that rotate circumferentially during movement of said handle members,

5 punch forcing means for forcing said punches radially inward in a direction toward intersection of said punches during portions of said circumferential movement of said punches,

10 said punch forcing means being selectively actuated by said pivotal movement of said handles to force said punches radially inward a distance proportional to the circumferential movement of said handles during the movement of said handles between actuation of said punch forcing means and said stop means,

15 gauge means coacting with said pivotal movement of said handles for actuating said punch forming means upon a given pivotal movement of said handles, means for selectively varying said gauge means to vary the point in said circumferential movement of said handles at which said punch forming means is actuated,

20 and locking means for locking said last mentioned means to a given point in said circumferential movement.

25 5. A crimping tool for attaching a connector to the end of a conductor comprising in combination:

30 first and second handle members pivotally interconnected at one of their ends and being capable of movement between open and closed positions, a set of punches radially disposed at said interconnection of said first and second handle members that rotate circumferentially during movement of said handle members,

35 punch forcing means for forcing said punches radially inward in a direction towards intersection of said punches,

40 said punch forcing means including punch holder means carried by said second handle member,

45 said punch holder means being rotatable circumferentially relative to said first handle member, gauge means secured to said punch holder means for preventing circumferential movement of said punch holder means when said gauge means contacts a spacer portion secured to said second handle member in said pivotal movement,

50 said punches being moved radially inward when said punch holder means is prevented from moving circumferentially,

55 and means positioned in said second handle member for selectively varying the amount of said spacer portion between said gauge means and said second handle member.

6. The machine of claim 5 wherein said spacer portion comprises a block having a stair-step shoulder portion, said block being slidable longitudinally along said second handle member in a manner that said steps may be selectively positioned to contact said gauge means upon the closing of said handles.

7. A crimping tool for attaching a connector to the end of a conductor comprising in combination:

first and second handle members pivotally interconnected at one of their ends and being capable of movement between open and closed positions, a set of punches radially disposed at said interconnection of said first and second handle members that rotate circumferentially during movement of said handle members,

punch forcing means for forcing said punches radially inward in a direction towards intersection of said punches,

said punch forcing means including punch holder means carried by said second handle member,

said punch holder means being rotatable circumferentially relative to said first handle member,

gauge means secured to said punch holder means for preventing circumferential movement of said punch holder means when said gauge means contacts a spacer portion secured to said second handle member in said pivotal movement,

said punches being moved radially inward when said punch holder means is prevented from moving circumferentially,

indentor control means positioned in said second handle member for selectively varying the amount of said spacer portion between said gauge means and said second handle member thereby selectively determining the movement of said punch holder, indicator means attached to said indentor control means for indicating the amount of radial movement of said punches,

ratchet means interconnected between said handle members for preventing disengagement of said punches from said connector until said handles have fully completed said pivotal movement,

and resilient means for resiliently biasing said gauge means from contact with said second handle member upon opening said handle members.
